CLAIM

The ornamental design for a planter, as shown and described.

DESCRIPTION

FIG. 1 is a front perspective view of a planter showing our design.

FIG. 2 is another perspective of the planter in FIG. 1.

FIG. 3 is a front elevation view of the planter in FIG. 1.

FIG. 4 is a rear elevation view of the planter in FIG. 1.

FIG. 5 is a left side elevation view of the planter in FIG. 1.

FIG. 6 is a right side elevation view of the planter in FIG. 1.

FIG. 7 is a top plan view of the planter in FIG. 1.

FIG. 8 is a bottom plan view of the planter in FIG. 1.

FIG. 9 is another perspective view of the planter in FIG. 1,

showing the planter in a first installation state; and,

FIG. 10 is another perspective view of the planter in FIG. 1,

showing the planter in a second installation state.

The broken lines in FIGS. 1-8 show portions of the planter that form no part of the claimed design. The broken lines in FIGS. 9-10 depict environmental structure and form no part of the claimed design.

1 Claim, 10 Drawing Sheets
